Henry B. Williams

UNITED STATES PATENT OFFICE.

WILLIAM GERAERDTS, OF NEW YORK, N. Y.

SHEET-LATHING.

1,311,441.

Specification of Letters Patent. Patented July 29, 1919.

Application filed June 19, 1916, Serial No. 104,361. Renewed December 24, 1918. Serial No. 268,162.

To all whom it may concern:

Be it known that I, WILLIAM GERAERDTS, a citizen of the United States, residing at the borough of Manhattan, city of New York, 5 in the county of New York, and State of New York, have invented certain new and useful Improvements in Sheet-Lathing, of which the following is a specification, reference being had therein to the accompanying drawings, forming part thereof.

My invention relates to sheet lathing adapted to be secured to the studding of walls and to ceiling beams for holding the plaster, and particularly to such sheet lathing made of sheets of paper or other suitable fibrous material held together by a suitable adhesive and having metallic stiffening and strengthening means.

A particular object of my invention is to 20 provide sheet lathing wherein the strengthening means are also highly effective as stiffening means and may be easily and simply applied to the flexible sheets without the use of prongs or fasteners, and will be securely held to the flexible sheets. Another object of my invention is to utilize the strengthening and stiffening means for the purpose of securely holding the plaster to the sheet lathing. Other objects and advantages of my invention will hereinafter appear.

I shall now describe my invention with reference to the accompanying drawings illustrating embodiments thereof and shall thereafter point out my invention in claims.

Figure 1 is a face view of a portion of a sheet of sheet lathing.

Fig. 2 is an enlarged cross-section including one of the strengthening and stiffening strips.

Fig. 3 is a similar view showing a modified form of strengthening and stiffening strip.

The sheet lathing as shown comprises an 45 outer layer 1 of absorbent paper or other fibrous or suitable material adapted to hold plaster, an inner layer 3 of paper or cardboard or any suitable sheet material, and an adhesive or cement 2 to hold the two layers together. In practice the inner layer 3 is usually heavier and stiffer than the outer layer 1.

In the use of sheet lathing it is necessary to provide transverse strengthening and 55 stiffening strips which are attached to the sheeting so as not to interfere with its flexi-

bility. These strips which are usually made of metal, are placed at suitable distances from each other on the sheet lathing, and it is customary to place them at distances 60 about equal to the distances between the studding or ceiling beams to which they are to be attached, though, of course, this distance can be varied whenever necessary.

As shown in cross-section in Fig. 2, my 65 strengthening strip is in contact with and is secured to the sheet lathing. The strengthening strip consists of a strip of metal having a fold 4 and having sides 6 and 7, both of which sides lie flat on the outer layer 1 70 of the sheet lathing.

The fold 4 is bent first to one side and then to the other so as to produce an undulating or staggered appearance. The sides thus bent over act to securely hold and lock the 75 plaster in place. The stiffening strip is formed and attached to the outer layer 1 of the sheet lathing as a preliminary step in the manufacture of the sheet lathing in the following manner: A flat strip of metal of 80 desired width is placed on the sheet of absorbent paper which forms the outer layer 1 of the sheet lathing, and the metal and paper are folded to form the fold 4, a paper fold 5 being formed and securely held in the 85 metal fold 4. The fold 4 is then bent as hereinbefore described. After these strips are supplied to the outer layer 1, it is ready for use in making up the sheet lathing. The usual perforations 9 may be provided in the 90 sheet lathing for more securely holding the plaster.

Fig. 3 shows a modification of my invention and consists of a strengthening strip attached to the outer layer 1 by box-plait 95 like fold 8, both sides of the fold being adapted to securely lock and hold the plaster in place.

It is obvious that various modifications may be made in the construction shown in 100 the drawings and above particularly described within the principle and scope of my invention.

I claim:

1. Sheet lathing consisting of two layers 105 of paper having an adhesive between them, and transverse strengthening strips secured to one of the layers of paper by folds in the strengthening strips inclosing and clamping within them folds in the layer of paper. 110

2. Sheet lathing consisting of an inner layer of non-metallic material, an outer layer

of fibrous material, an adhesive between them, and transverse metallic strengthening strips secured to the outer layer by folds in the strengthening strips inclosing and clamping within them folds in the outer layer.

3. Sheet lathing consisting of an inner layer of non-metallic material, an outer layer of fibrous material, an adhesive between them, and transverse metallic strength-

10 ening strips secured to the layer of fibrous material by folded portions inclosing folds in the layer of fibrous material, such folded portions overhanging to hold the plaster.

4. Sheet lathing consisting of an inner 15 layer of non-metallic material, an outer layer of fibrous material, an adhesive between them, and transverse metallic strengthening strips secured to the layer of fibrous material by folded portions inclosing folds

20 in the layer of fibrous material, such folded

portions overhanging on both sides of the strips to hold the plaster.

5. Sheet lathing consisting of two layers of paper having an adhesive between them, and transverse metallic strengthening strips 25 secured to one of the layers of paper by folds in the strips inclosing folds in the layer of paper, the folds in the strips overhanging to hold the plaster.

6. Sheet lathing consisting of two layers 30 of paper having an adhesive between them, and transverse metallic strengthening strips secured to one of the layers of paper by folds in the strips inclosing folds in the layer of paper, the folds in the strips over- 35 hanging on both sides of the strips to hold the plaster.

In testimony whereof I have affixed my signature.

WILLIAM GERAERDTS.

Copies of this patent may be obtained for five cents each, by addressing the "Commissioner of Patents, Washington, D. C."
